UNITED STATES PATENT OFFICE.

ELIHU THOMSON, OF SWAMPSCOTT, MASSACHUSETTS, ASSIGNOR TO THE THOMSON-HOUSTON ELECTRIC COMPANY, OF CONNECTICUT.

ELECTRIC CUT-OUT.

SPECIFICATION forming part of Letters Patent No. 508,652, dated November 14, 1893.

Application filed September 17, 1891. Serial No. 406,008. (No model.)

To all whom it may concern:

Be it known that I, ELIHU THOMSON, a citizen of the United States, residing in Swampscott, in the county of Essex and State of Massachusetts, have invented certain new and useful Improvements in Electric Cut-Outs, of which the following is a specification.

My present invention relates to electric cut-offs for cutting off or breaking an electric circuit on occurrence of an abnormal current therein. It is particularly to be applied to cutting off circuits in which the potentials are high enough to maintain arcs of considerable length, as to the case of cutting off 10 former primary circuits, or interrupting the connection between the primary mains and the primary coils of transformers when for any reason a short-circuit of the primary, or short-circuit of the secondary of the transformer has occurred, or to the case where a short-circuit through lightning protective devices has been formed.

My invention provides a simple arrangement for cutting off arcs abnormally forming either to ground or between the sides of a circuit at high potential difference; my invention relating both to the particular device which is used as a cut-off and to the general combination with the circuit of a device having the functions which are to be described.

One of the features of my invention is that the interruption of the circuit is accomplished by drawing open the contact pieces and carrying one or both of them down into a body 35 of oil which extinguishes the arc. One part of my invention, therefore, is broadly a switching device the contact parts of which are normally supported in air but which, on the formation of an arc, are immersed in a body 40 of oil.

Another feature of my invention is the restoring action of the circuit breaker on the interruption of an arc and the final locking of the arrangement in an open position when 45 after several restorations the abnormal conditions of short-circuit are shown to remain.

In the accompanying drawings Figure 1 is a vertical section of a cut-off embodying my invention. Fig. 2 is a plan of the same. 50 Figs. 3 and 4 are diagrams of systems with

my invention applied thereto. Figs. 5 and 6 show modifications.

Referring first to Fig. 3 A is a source of high potential currents, in this case alternating currents connected to mains M leading to 55 primary coil P of an induction coil or transformer, while S is the secondary coil of said transformer, and L, L, may be lights or other devices in the circuit thereof. At E, E' and F are lightning arrester plates, the plate F 60 being grounded at G, while the plates E, E' slightly separated both from the ground plates and from each other form discharge electrodes in shunt across the terminals of the primary P. At K is placed my cut-off device, 65 acting to interrupt the connection between the mains M and the transformer on excessive current flowing as on a short circuit in the primary or secondary, or acting to interrupt the connection of the mains M to the discharge plates E, E' on the occurrence of a short-circuit or arcing either between the plates E, E' or between either of the plates 70 and the ground plate F, such arcing being induced by lightning discharges between such 75 plates. Interruption of the connection of the mains M in the manner stated would of course extinguish any arc at the discharge plates, or stop any short-circuit which might occur.

Fig. 4 shows the application of the cut-off 80 apparatus directly to a system in which there is no transformer. K is a cut-off apparatus, and E, E' and F are the arrester plates, as before, while the line connections are carried directly to the translating devices, such as 85 motors on a five hundred volt circuit, indicated at L, L. In such case currents due to short-circuits would be disastrous if the apparatus were not provided with devices to open circuit it when such short-circuits were 90 formed. This my cut-off apparatus K is designed to do.

In Figs. 1 and 2, B, B, is a box containing preferably some non-conducting oil O, above which is a clear space. The box is provided 95 with a lid B' which enables access to be had to its interior. At C is mounted an insulated contact which may be made of a carbon block. A contact lever D bears upon the contact block C, being held against the same 100

by the action of a spring S'. The lever D is pivoted, as shown, preferably beneath the surface of the oil. Lever D and contact C are connected in the circuit through connections 5 m, n. In the connection to lever D is inserted a coil H, which when abnormally energized by current attracts or pulls an armature or core I, attached to or arranged to actuate the lever D depressing it and carrying its contact surface resting on the block C down beneath the oil surface and thus interrupt any arc which may form between the contacts, or which may tend to continue after the lever D is drawn away from the block C. 15 The armature or core I in the case of alternating currents may be made laminated as is well understood, and its motion may be retarded by a confined body of oil acting as a dash-pot in various ways. A separate dash- 20 pot might be provided but I have shown the core entering into its coil which forms an oil cylinder. It is desirable that the descent of the lever D and the core I shall be made quickly and hence I provide a valve V which 25 allows the oil to escape out of the piston core I and into the general oil space when the core begins to descend. When the descent has been accomplished and the arc is interrupted, the spring tends to raise the lever D on account of the core having been released from 30 the attraction of the coil. The release, however, on account of the closure of the valve V is made slowly and continues until the contact is again formed at C when if the abnormal conditions which provoked the descent of 35 the lever D still exist, the actions above referred to would be repeated indefinitely were it not for other provisions which I have made. If therefore permanent harm has been done 40 or permanent short-circuits have been caused the repeated opening which thus takes place calls attention to the condition of the apparatus, and at the same time is apt to be noticed at the generating station. However, I 45 provide in some cases an additional device the purpose of which is to lock the lever D down and out of contact with the block C upon the occurrence of a permanent short circuit demanding its repeated action. Many 50 ways of accomplishing this result could be devised and I only indicate one of them. At each descent of the piston core I, the oil under it imparts motion to the oil in the tube T, at the end of which is a small valve W which lifts and allows at about the time that the valve V is lifted, a small gush of oil to work into the cylinder J, in which plays a loosely fitting piston which when it rises to a certain extent throws a catch or pawl into engagement 55 60 with the toothed edge of the lever D. The amount of flow is regulated so that it requires a repeated action of the piston core I, to force enough oil over into the part J to cause the engagement of the pawl at R with the toothed portion carried by the lever D. When the pawl at R is thrown into engagement, lever D remains down and out of contact and all

action ceases while the line n remains open-circuited or out of connection with the line m. The locking device is preferably so constructed that there is required for the continued lift of the piston in the cylinder J a succession of pumping actions or movements of oil at not too great intervals apart, that is that the switch lever must be vibrating up and down within moderate intervals in order to continue to cause the piston in the cylinder J to ascend to the position required for locking the pawl detent R. This is accomplished by allowing the piston in the cylinder J to have a slight leakage whereby if the repetition of the actions of forcing oil is not made at sufficiently short intervals the piston drops back to its first position. In such case the actions which would call the device into operation at considerable intervals, such as would occur during thunderstorms by successive flashes would not cause the locking of the switch lever D down, but a permanent short-circuit occurring on the line n would be followed at every contact of the lever D with a quick separation and immediate return to contact and again an instantaneous separation, this action being rapidly repeated. In such case the cylinder J would be unable to leak the fluid which was constantly accumulating and the ratchet pawl R would be thrown into engagement so as to hold the switch lever D open. The lever D having been thus locked, it may be released by opening the box and depressing the piston rod by button Q so as to release the catch.

Fig. 2 is a view looking down into the box B, B, and shows a duplication of parts whereby the apparatus is made to act on both poles of a circuit or become a double pole arrangement. Both of these may be immersed in the same oil chamber or the sets could be put into separate oil chambers if desired, and both act together to interrupt short-circuits or disconnect the line, or they might act separately when the devices are such as to demand separate action.

In many cases the locking devices above described would be unnecessary, as where it is only desired to rupture short-circuits between arrester plates due to momentary lightning discharges, the circuit being automatically restored to normal condition. As thus simplified, the apparatus is shown in Fig. 5. In this case the valve V may be placed directly below the cylinder in which the core I moves, or as before, the lever D may be provided with a separate dash-pot having a valve similarly placed.

The means for extinguishing an arc, which consists in a non-conducting body of liquid beneath the arcing terminals, and into which one or both of said terminals are dipped when an arc is formed, may be applied to any forms of apparatus in which arcs are liable to form. Fig. 6 shows the principle applied to a simple hand switch, D being the switch lever, C its contact and O the body of oil.

What I claim as new, and desire to secure by Letters Patent, is—

1. A device for rupturing arcs between terminals, consisting of a body of non-conducting liquid, terminals arranged normally above said liquid, and means for immersing at least one of them in said liquid when they are separated, substantially as described.
2. The combination with a closed box, of a body of non-conducting liquid partially filling the same, a terminal of an electric circuit arranged above the surface of said liquid, and a second terminal in contact therewith and arranged to move below the surface of the liquid when separated therefrom, substantially as set forth.
3. The combination with a closed box, of a body of non-conducting liquid partially filling the same, a terminal of an electric circuit arranged above the surface of the liquid, a lever forming a second terminal in contact with the first, and an electro-magnetic device operating to separate said terminals and immerse the lever in the liquid, substantially as described.
4. An electric switch having a fixed and a movable terminal, and a body of non-conducting liquid below such fixed terminal and in the path of such movable terminal.
5. A device for rupturing arcs between electric terminals, consisting of a body of non-conducting liquid below such terminals, and means for immersing one of such terminals in such liquid, consisting of an electro-responsive device connected to such terminals.
6. A device for rupturing arcs between terminals consisting of a body of non-conducting liquid below such terminals, and an electro-magnetic device connected mechanically to and electrically to such terminals, and acting to immerse at least one of them in such liquid on the passage of a current therethrough.

7. A switch included in and protecting an electric circuit and having an electro-magnetic device controlling and separating its contacts, an automatic locking device for holding such contacts apart, and means for throwing said detent automatically into locking position only by the repeated separation of the contacts.

8. A switch included in and protecting an electric circuit, and having an electro-magnetic separating device for its contacts, a restoring device for the same, and a locking device for locking the contacts apart and connected to the electro-magnetic devices, so as to be operated only by the repeated action thereof.

9. A switch included in and protecting an electric circuit, and having an electro-magnetic separating device for its contacts, a restoring device for the same, and a retarded locking device for locking the contacts apart and tending to an unlocking position, and connected to the electro-magnetic devices by a slowly yielding connection, allowing return into unlocking position of the locking devices between widely separated impulses of the electro-magnetic devices, and bringing the locking devices into operation when such impulses are in rapid succession.

10. The combination with two separable terminals, of a submerged solenoid, and a movable core connected with one of said terminals, whereby said solenoid and core form a dash pot to regulate the movements of said terminals, substantially as described.

In witness whereof I have hereunto set my hand this 14th day of September, 1891.

ELIHU THOMSON.
